UNITED STATES PATENT OFFICE.

MARVIN R. TEDRICK, OF PLAIN CITY, OHIO.

LUBRICATING MECHANISM.

Application filed December 16, 1924. Serial No. 756,288.

To all whom it may concern:

Be it known that I, MARVIN R. TEDRICK, a citizen of the United States, residing at Plain City, in the county of Madison and State of Ohio, have invented a certain new and useful Improvement in Lubricating Mechanism, of which the following is a specification.

The invention as herein shown is intended more particularly to automatically lubricate all the distinct parts and bearings of an automobile chassis and the object of the invention is to provide an improved mechanism of simplified and compact form that may be conveniently connected for operation with the transmission gear or drive shaft of the automobile so as to feed the oil in the proper quantity or without considerable under or over lubrication.

The invention is embodied in the example illustrated in the accompanying drawings and set forth in the following specification, the features of novelty being finally claimed.

In the accompanying drawings—

Figure 1 is a top plan view of the oil reservoir and its contained mechanism as it appears with the cover removed.

Fig. 2 is a vertical section on the line II—II Fig. 1 looking to the left.

Fig. 3 is a similar view on the line III—III looking in the same direction.

Fig. 4 is a detail in elevation of a part of the timing mechanism.

Fig. 5 is a vertical section on the line V—V Fig. 2 illustrating the pumping mechanism.

Fig. 6 is a top plan view of the valve plate used in the pumping mechanism.

Fig. 7 is a view partially in horizontal section on the line VII—VII Fig. 2 to illustrate the gear train from the main drive.

Figs. 8 and 9 are side and interior views respectively of a member of the expandible nut used in the mechanism.

In the views 10 designates the oil box or lubricant reservoir, said box being provided with a suitable removable end 11^a and cover 11. The bottom of the box along one side has two series of holes 12 with which are connected suitable pipes 13 ramified to the various bearings or parts of the chassis to be lubricated. Lying on the bottom of the box above the holes 12 is a valve plate 14 (see Fig. 6) provided with two parallel series of discharge holes 15 corresponding in relative position to the holes 12 in the

bottom of the box so that in one position of the plate said holes shall align with the holes 12 in the bottom of the box, said plate also being provided in its upper side with a series of gutters 16 terminating in round pockets so that when said plate is longitudinally moved to close the holes 12 the gutters 16 are placed into position to admit lubricant to the pump cylinders as will be presently set forth. Secured in the bottom of the box above the plate 14 is the pump block 17 formed with cylinders 18 corresponding in number to the outlets 12 and having ports 19 at their lower ends adapted in operation to align alternately with the holes 15 and the pockets of the gutters 16. In the cylinders 18 are pistons 20 having springs 21 engaging heads 22 on the upper ends of the pistons, said springs adapted to lift the pistons upward and suck oil into the cylinders from the reservoir through the gutters 16 and ports 19 (see Fig. 2). When the plate 14 is longitudinally shifted from the position shown in Fig. 2 and the holes 15 aligned with ports 19 and holes 12 downward pressure of the pistons 20 forces lubricant into pipes 13 and to the bearings or parts to be lubricated. It may be here noted that the cylinders or both the cylinders and the ports can be made of various sizes, as shown or otherwise, so as to vary the quantities of lubricant discharged according to the requirements of the various bearings or parts to be lubricated.

Journaled horizontally between the ends of the box and above the upper ends of the pistons are cam shafts 23 and 24 adapted when rotated, first to depress the pistons and then permit them to rise due to the action of the springs on them. Because it is my purpose to operate these pistons from the transmission gear of the motor vehicle it is important that intervening mechanism be provided for a great reduction from the normal speed of that gear. The mechanism of my invention in this respect is best illustrated in Fig. 7. In that view and also in Fig. 1 the character 25 designates the spur gear that is meshed or connected with the transmission gear (not shown) or with a gear on the drive shaft, said gear 25 being keyed on a shaft 26 that is journaled in a bearing 40 in the end of the oil box and a bracket arm 27 secured on the box. The shaft 26 has a pinion 28 fixed thereon engaging a large gear 29 loose on a shaft 30 said large gear carrying planetary

2
pinions 31 meshing with a spur gear 32 keyed on said shaft 30. The shaft 30 is journaled at one end in the end of the oil box and at the other in a small bracket 33 so that its axis of rotation coincides with the corresponding axis of the cam shaft 24; and that portion of the shaft 30 within the box constitutes a bearing for a stud shaft of said cam shaft 24. The shaft 30 also has 10 formed on it a pinion 34 and a clutch member 35 to which latter further reference will be made. The pinion 34 engages a large spur gear 36 carrying planetary pinions 37 meshing with a spur gear 38 keyed on a timer shaft 39, said timer shaft being journaled in the bearing 40 before referred to in line with the axis of the shaft 26. The timer shaft 39 has fixed or formed on it a large worm screw 39^a of slow pitch engaged 15 by the longer arms 41 of a forked or expandible yoke or nut, said arms being provided at their inner sides with threads complementing those of the worm (see Figs. 8 and 9). A spring 42 connects the arms 41 so that they are drawn toward each other and to embrace and engage the worm. The shorter arms 43 of the expandible nut embrace a flat bar 44, said bar provided at one end with a stop 44^a and journaled at that 20 end in a block 45. At its other end the bar 44 is provided with a forked crank arm 46 carrying an anti-friction roller 47 impinged by a cam 48 on cam shaft 24 as hereinafter explained. The arms 41—43 are pivoted together, somewhat like the members of a pair of ordinary pinchers, on a pin 49 extending between uprights 50—50 on a sliding frame 51, and when the flat bar 44 is rocked by the crescent action of the cam 48 said bar separates the shorter arms 43 and also the arms 41 removing the latter from engagement with the worm 39^a. When the anti-friction roller 47 is on the low part of the cam 48 and the worm 39^a is rotated in the regular 25 operation of the mechanism the sliding frame 51 is fed to the left by the action of the worm on the nut. The sliding frame 51 has at its left hand end a laterally extending arm 52 provided with an anti-friction roller 53 acted on by the spirally formed cam edge 54 on sleeve 55 splined on an axial extension of the cam shaft 24. The sliding frame 51 slides on another sliding member 56 having at its left hand end a lateral extension provided with a yoke 57 that is mounted in a slot 57^a on said arm and engages an annular groove in a clutch member 58, said clutch member being slidably splined on the aforesaid reduced axial extension of the cam shaft 24. The sliding members 51—56 are supported on a block 75 under a clip 76 secured to the block. Said clutch member 58 engages and is operated by the clutch member 35, before referred to. The right hand end of the sliding member 56 is provided with an abut-

ment 59 against which the right hand end of the slide 51 thrusts when the cam edge 54 operates on the roller 53 upon the engagement of the clutch member 58 with the clutch member 35. The engagement of the roller 53 with the cam edge 54 thrusts the clutch member 58 into engagement with the clutch 35. The slide member 56 is provided with a V-shaped trip projection 61 cooperating with a spring actuated pin having a V-shaped head 60 so that the clutch member 58 is snapped into and yieldingly latched in engagement with the clutch member 35 when the sliding member 56 is moved to the left; and snapped out of engagement when said slide is shoved to the right by the thrust of the slide 51 against the abutment 59.

70 After the clutch 58 is engaged with the clutch 35 the cam 54 operates on the roller 53 the jaws 41 being opened by the action of the cam 48 the cam 54 operating on the roller 53 to retrieve the yoke nut 41 to starting position.

80 It will be assumed that the reservoir is filled or sufficiently supplied with oil.

90 The pump valve plate 14 is reciprocated to open the lubricant discharge ports just prior to the operation of the cam shafts 23 and 24 to effect a down stroke of the pistons and to close said ports and place the supply gutters into position to admit lubricant to the cylinders at the initiation of the upward movement of the piston under the action of their springs 21 by means of a lever 63 hinged at 64 in an ear 65 at the right hand end of said plate and fulcrumed on a pin 66 on a suitable ear 67 on the pump block, said lever 63 entering for that purpose an annular cam groove 68 in a sleeve 69 fixed axially on the cam shaft 23. The two cam shafts 23 and 24 are geared together to rotate in unison by means of gears 70 and 71 fixed axially on said shafts respectively.

100 The operation which can be readily understood from the foregoing may be briefly summarized as follows:

110 The motion imparted to the worm 39^a by the train of gearing is constant during the operation of the transmission gear or the drive shaft of the motor vehicle. Assuming that the parts are in the position shown in Fig. 1 the expandible nut 41 is engaged with the worm, the cam shafts 23 and 24 remain idle until the clutch member 58 is thrust by the slide 51 into engagement with the clutch member 35. During this engagement the two cam shafts 23 and 24 are rotated once operating the pumps until the slide 51 is shifted to the right by the cam 54 to strike the abutment 59 thus releasing the clutch member 58. The releasing of the clutch 58 is slightly delayed by reason of the slot 57^a to permit proper operation of the cam, it being remembered that the rotation of the cam 48 releases the expandible nut 41 from the 120 130

worm to permit the retrieving of the nut longitudinally over the worm to starting position. Upon the completion of the rotation of the cam shaft 24 the nut is restored to engagement with the worm 39^a and the operation repeated. During the operation of the cam shafts 23 and 24 the valve plate 14 is first shifted to open the discharge ports and then shifted to close them for refilling the pump cylinders. There is thus an intermittent rotation of the two cam shafts 23 and 24 and an operation of all the pumps by direct action on them of the cam shafts. The rate of rotation of the cam shafts is somewhat greater than the rate of rotation of the worm shaft because of the difference in gearing the construction being such as to adapt it for adequately lubricating the different parts necessary to be lubricated for which the apparatus is installed.

The forms of the parts can be changed without departing from the gist of the invention as claimed.

What I claim is:

1. Mechanism for lubricating a plurality of distinct parts comprising, in combination, a lubricant reservoir having discharges to the parts to be lubricated, two series of pumps for said discharges and containing pistons therein, a movable valve plate common to the two series of pumps and the discharges thereof, said valve plate provided with a plurality of pump feeding and discharging ports and adapted to be reciprocated to alternately and simultaneously open and close the several discharges of said pumps, means for actuating said pump pistons consisting of two cam shafts geared together and each shaft adapted to act directly on a series of said pistons to move them in one direction, springs for moving the pistons in the opposite direction, means for automatically intermittently rotating said cam shafts, and means actuated by one of said cam shafts for reciprocating said valve plate.

2. Mechanism for lubricating a plurality of distinct parts comprising, in combination, a lubricant reservoir, a series of pumps and pistons therein for supplying lubricant to said parts to be lubricated, a cam shaft common to the series of pistons to act directly on said pistons, driving means for said cam shaft, means for connecting and disconnecting the cam shaft from its driving means and means actuating the same to cause the intermittent rotation of said cam shaft.

3. Mechanism for lubricating a plurality of distinct parts comprising, in combination, a lubricant reservoir, a series of pumps and pistons therein for supplying lubricant to said parts to be lubricated, a cam shaft common to the series of pistons to act directly on said pistons, driving means for said cam shaft, a clutch mechanism for con-

nnecting and disconnecting the cam shaft from its driving means, means for actuating said clutch to cause the intermittent operation of said cam shaft.

4. Mechanism for lubricating a plurality of distinct parts comprising, in combination, a lubricant reservoir, a series of pumps and pistons therein for supplying lubricant to said parts to be lubricated, a cam shaft common to the series of pistons to act directly on said pistons, driving means for said cam shaft, a clutch mechanism for connecting and disconnecting the cam shaft from its driving means, means for actuating said clutch to cause the intermittent operation of said cam shaft including a worm and a nut removable therefrom adapted to be fed by the worm to shift said clutch.

5. Mechanism for lubricating a plurality of distinct parts comprising, in combination, a lubricant reservoir, a series of pumps and pistons therein for supplying lubricant to said parts to be lubricated, a cam shaft common to the series of pistons to actuate them, driving means for said cam shaft, a clutch mechanism for connecting and disconnecting the cam shaft from its driving means, means for actuating said clutch to cause the intermittent operation of said cam shaft including a worm and a nut removable therefrom adapted to be fed by the worm to shift said clutch in one direction.

6. Mechanism for lubricating a plurality of distinct parts comprising, in combination, a lubricant reservoir, a series of pumps and pistons therein for supplying lubricant to said parts to be lubricated, a cam shaft common to the series of pistons to actuate them, driving means for said cam shaft, a clutch mechanism for connecting and disconnecting the cam shaft from its driving means, means for actuating said clutch to cause the intermittent operation of said cam shaft including a worm and a nut removable therefrom adapted to be fed by the worm to shift said clutch in one direction and means for returning said nut in the opposite direction.

7. Mechanism for lubricating a plurality of distinct parts comprising, in combination, a lubricant reservoir, a series of pumps and pistons therein for supplying lubricant to said parts to be lubricated, a cam shaft common to the series of pistons to actuate them, driving means for said cam shaft, a clutch mechanism for connecting and disconnecting the cam shaft from its driving means, means for actuating said clutch to cause the intermittent operation of said cam shaft including a worm and a nut removable therefrom adapted to be fed by the worm to shift said clutch in one direction and means for returning said nut in its removed position in the opposite direction consisting of a spiral cam on said cam shaft.

8. Mechanism for lubricating a plurality

of distinct parts comprising, in combination, a lubricant reservoir, a series of pumps and pistons therein for supplying lubricant to said parts to be lubricated, a cam shaft common to the series of pistons to actuate them, driving means for said cam shaft, a clutch member on said cam shaft for connecting and disconnecting the cam shaft from its driving means, means for actuating said clutch to cause the intermittent operation of said cam shaft including a worm and a nut

removable therefrom adapted to be fed by the worm to shift said clutch member in one direction and means for returning said nut in removed position in the opposite direction consisting of a spiral cam member also on said cam shaft, said clutch and spiral cam members being longitudinally movable on the cam shaft independently of each other. 15

MARVIN R. TEDRICK.
